Patented Nov. 2, 1976

242,116

CHAIN GRAB LINK OR SIMILAR ARTICLE

Gerald R. Mooney, 3080 Eldogor Lane 16105, and
Louis A. Mooney, 1002 Ryan Ave. 16101, both of
New Castle, Pa.

Filed Sept. 18, 1975, Ser. No. 614,527

Term of patent 14 years

Int. Cl. D8—08

U.S. CL. D8—261

FIG. 1

FIG. 2

FIG. 4

FIG. 3

FIG. 5

FIG. 6

FIG. 8

FIG. 7

FIG. 1 is a top plan view of a chain grab link or similar article embodying our new design, with the bottom being a mirror image of that shown;

FIGS. 2—4 are sectional views, taken along the lines 2—2—4—4 respectively, of FIG. 1;

FIG. 5 is a top plan view of a second embodiment of a chain grab link or similar article embodying our new design, with the bottom being a mirror image of that shown;

FIGS. 6—8 are sectional views, taken along the lines 6—6—8—8, respectively, of FIG. 5.

We claim:

The ornamental design for a chain grab link or similar article, as shown and described.
